US00D525720S

(12) **United States Design Patent** (10) **Patent No.:** **US D525,720 S**
(45) **Date of Patent:** **** Jul. 25, 2006**

(54) **CORBEL**

(75) Inventor: **Beverly Ellsley**, Westport, CT (US)

(73) Assignee: **The Enkeboll Company**, Carson, CA (US)

(**) Term: **14 Years**

(21) Appl. No.: **29/226,316**

(22) Filed: **Mar. 28, 2005**

(51) **LOC (8) Cl.** **25-02**

(52) **U.S. Cl.** **D25/55**

(58) **Field of Classification Search** D25/136, D25/55, 145, 148, 135, 126, 151; 52/273, 52/255, 290, 316, 287.1, 2.21, 301, 302.5; 256/1; 428/15, 28, 29, 542.2, 542.8; D6/493

See application file for complete search history.
